UNITED STATES PATENT OFFICE.

FREDERICK M. OEHLEY, OF YONKERS, NEW YORK.

DESIGN FOR A BADGE.

SPECIFICATION forming part of Design No. 26,375, dated December 8, 1896.

Application filed September 18, 1896. Serial No. 606,305. Term of patent 31 years.

To all whom it may concern:

Be it known that I, FREDERICK M. OEHLEY, a citizen of the United States, residing at Yonkers, in the county of Westchester and State of New York, have invented and produced a new and original Design for Badges, of which the following is a specification, reference being had to the accompanying drawing, showing a part thereof.

10 My invention relates to a design for badges, the present invention being more particularly intended for use as a campaign-badge. The accompanying drawing shows the present badge.

15 Referring now more particularly to this drawing, *a* represents a spray of golden-rod having the stem *a'* with a leaf *a²* upon said

stem at the base of the spray, this leaf forming a portion of a background for the spray. Upon the leaf may be stamped or otherwise 20 formed any suitable inscription. A suitable pin *b* is provided for attaching the badge to the coat or other suitable article.

The present design is neat in appearance and thoroughly distinctive.

Having thus described my invention, what I claim as new, and desire to secure by Letters Patent, is—

The design for a badge substantially as herein shown and described.

FREDERICK M. OEHLEY.
